DELIVERY MECHANISM FOR PRINTING MACHINES

Filed July 20, 1925

2 Sheets-Sheet 2

UNITED STATES PATENT OFFICE.

FRED WAITE, OF INGLEWOOD, OTLEY, ENGLAND.

DELIVERY MECHANISM FOR PRINTING MACHINES.

Application filed July 20, 1925. Serial No. 44,709.

To all whom it may concern:

Be it known that I, FRED WAITE, a subject of the King of Great Britain, and resident of Inglewood, Otley, in the county of 5 York, England, have invented certain new and useful Improvements in Delivery Mechanism for Printing Machines, of which the following description, having reference to the accompanying sheets of drawings, is a 10 specification.

My invention relates to printing machines wherein the printed sheets as they are delivered from the printing cylinder are received by grippers carried by traveling 15 chains which carry said sheets along their path of delivery with their printed or face sides downwards and deposit same on a table or other device with their said printed or face sides upwards and my said invention 20 consists in the application of sheet supporting bars which extend crosswise from the delivery chain on one side to the delivery chain on the other in such manner that when the grippers carried by the usual 25 traversing or cross shafts engage the leading edge of a printed sheet they carry such edge forward while the body of the sheet lies relatively at the rest upon the supporting cross-bars of the chains until the position 30 is reached where the sheet commences to turn in a downward direction prior to being deposited face upwards; and in this position I also provide receiving means which will receive the rear end of the sheet 35 so that as said rear end commences to follow its downward path from its upper horizontal path to the position which it ultimately occupies in the pile of sheets below, its rear end is received and supported by 40 devices which conduct it and carry it so that the whole sheet moves above and over the printed sheets beneath in such a manner that when the second supporting devices are withdrawn by a reversal of their motion 45 they permit the rear edge of the sheet to descend gradually and simultaneously with the descending of the front edge of the sheet as this is released by the grippers on the chain, thus each printed sheet is carried throughout its whole path and deposited in 50 the position desired with the least liability of any of said sheets being creased or smeared at any part by trailing one sheet over another while said actions are being carried out.

In order that my said invention may be

readily understood, I have hereunto appended sheets of drawings illustrative thereof wherein:

Fig. 1 is a side elevation of sufficient 60 of a printing machine to show the application thereto of my improved delivery mechanism.

Fig. 2 is a plan of the parts shown by 65 Fig. 1.

Fig. 3 is a section taken longitudinally of a part hereinafter described, said view being drawn to an enlarged scale.

A indicates the end frames of the 70 machine.

According to my invention I arrange the two side chains 2 and 2^a in the position shown so that as the printed sheets are delivered by the gripped cylinder 3 face downwards to said chains 2 and 2^a, one or other of the sets of grippers 4 thereon will lay hold of the leading edge of each of said sheets (such as the sheet *a* shown by Fig. 2) and carry same face downwards along the upper portion *b* of the chains as shown by Fig. 1. In order to support the rear ends of the sheets as these latter are carried in the paths described, I arrange supporting members, preferably in the form of cross tubes 8 to extend from the chain 2 on one 75 side to the chain 2^a on the other side, and be secured to said chains in manner herein-after explained.

As stated although I preferably make use 90 of cross tubes 8, it is obvious that solid or flat flexible bars may be used, or even cords or fabrics may be employed for supporting the rear ends of the sheets.

The printed sheet carried as above explained will rest face downwards upon one 95 or other of the series or sets of cross bars 8 which extend from the chain 2 to the chain 2^a throughout the whole length thereof.

The chains 2 and 2^a are carried over 100 sprocket wheels 5, 5^a at the end of the machine and forward from the sprocket wheels 5, 5^a they extend over guiding wheels 6 and 6^a to finally pass around the sprocket wheels 9 and 9^a which bring them into appropriate 105 proximity to the cylinder 3. The grippers 4 are caused to grip and to release their said grip upon the sheet, by devices well known in connection with printing machinery.

In combination with the chain devices arranged as above described I also make use 110 of curved guiding members 10 which are fixed upon cross bars 11 that are mounted

upon the outer ends of bifurcated levers 12, 12^a which are mounted to swing loosely upon the shaft *d* about which the sprocket wheels 5, 5^a revolve.

The bifurcated lever 12 has a third arm 13 to which is pivoted a connecting rod 14 that reaches to be connected to a lever 15 which is mounted upon a shaft *f* mounted upon bearings 16 fixed upon the framework 19 A of the machine and fixed upon the other end of this shaft *f* is another lever 17 which by a connecting rod 18 is coupled to a lever arm 19 which has another arm 20 fixed upon it so that the lower end of this arm 20 may have pivoted upon it a runner or bowl 21 for contact with the peripheral surface of a cam 22 that is fixed upon the shaft of a driving wheel 23 which derives its motion from any suitable motor shaft of the machine as will be understood.

The cam 22 is arranged to revolve at the desired speed relative to the surface speed of the chains 2, 2^a so that when any of the grippers 4 carrying the leading edge of a sheet have advanced sufficiently far for the rear edge of said sheet to be brought beyond being in alignment with the centre of the shaft *d* then the curved supporting members 10 will be raised into the position shown in broken lines Fig. 1 and from this position, as the chains 2, 2^a and their grippers 4 continue in motion to carry forward the sheet referred to, the cam 22 will have advanced sufficiently forward to permit the spring 24 to recoil and bring down the curve members 10 which under the control of the cam 22 will be at the same speed and in unison with the motion of the sheet carried by the grippers 4 thus any tendency that the rear end of the sheet may have to move beyond the desired curved path which it has to follow, is prevented by the curved members 10 (which receive that part of each sheet) and these continue their motion along with the sheet until the grippers 4 have reached the position where it is desirable that they should deposit the sheet upon the pile of sheets at *g* so that just prior to the releasing of said grippers the curved supporting members 10 will commence to recede in order that the sheet may be permitted to fall by gravity directly on to the pile of sheets *g* beneath thus all tendency to cause any sheet to be dragged or trailed over any printed part of any preceding sheet is entirely avoided.

The return motion of the curved supporting members 10 as before stated, is effected by the actions of a cam 22 at the desired speed so that the upper ends of the curved members 10 will reach the position shown in broken lines Fig. 1 at about the same time that the rear end of the next or succeeding sheet has reached the same position.

As is hereinbefore stated I preferably make use of hollow or cylindrical cross bars 8 in order that the whole chain and the parts it carries may be as light as possible, and in order to be enabled to readily detach or mount anyone of said bars 8 from its position and into its position on the chains 2 and 2^a I have the links of the said chains coupled together by hollow pins or rivets 30. This enables me to employ plugs 31 which I mount in the outer ends of the tubes or bars 8 so that same may take into the said openings in the rivets 30.

The plug 31 is fixed by a pin 31^a in the end of the tube 8 as is shown by Fig. 3 while so the plug 31^b at the opposite end is made to slide longitudinally into the end of said tube 8 where it is normally held in the position shown by Fig. 3, by a spring 32 resting against it and against a cross pin 33 fixed within the tube, thus by forcing the plug 31^b endwise into the tube 8 until it is clear of the rivet 30 the said tube 8 may be removed whereas on desiring to replace said tube in position, the plug 31^b may be forced into the interior thereof until the tube is brought into alignment with the hole in the rivet 30 on which by releasing the hold of said plug the spring 32 is permitted to recoil in order to force said plug outwardly to enter the hole in the rivet 30.

Such being the nature and object of my said invention, what I claim is:—

1. In delivery mechanism for printing machines, travelling chains, grippers carried by said chains, sprocket wheels over which said chains are made to take, means for transmitting motion to said sprocket wheels, means extending between and carried by said chains to support the rear portion of the sheets and devices for receiving and depositing the printed sheets as delivered by said chain and released by the grippers thereon.

2. In delivery mechanism for printing machines, travelling chains, grippers carried by said chains, sprocket wheels over which said chains are made to take, means for transmitting motion to said sprocket wheels, series of cross bars extending from one chain to the other, oscillating members for receiving and depositing the printed sheets as delivered by said chains and released by the grippers thereon, and means for operating said oscillating members to receive each sheet successively and deposit same on the sheets beneath.

3. In delivery mechanism for printing machines, travelling chains, grippers carried by said chains, sprocket wheels over which said chains are made to take, means for transmitting motion to said sprocket wheels, means for supporting the rear ends of the sheets carried by the chains, oscillating arms supporting members which are oscillated in proximity to the travelling chains,

cam and spring devices for operating said oscillating arms and members and means for receiving the sheets deposited by said oscillating members.

- 5 4. In delivery mechanism for printing machines, travelling chains, grippers carried by said chains, sprocket wheels over which said chains are made to take, means for transmitting motion to said sprocket wheels, series of cross bars detachably mounted upon said chains, said cross bars having fixed and spring actuated pivotal connections for engaging with the rivets of the chains, devices for receiving the printed

sheets as delivered by the chains and means 15 for receiving the delivered sheets.

5. In delivery mechanism for printing machines, travelling chains, grippers carried by said chains, sprocket wheels over which said chains are made to take, means 20 for carrying the rear ends of the sheets mounted upon said chains, curved oscillating members mounted to oscillate in paths approximately parallel to the curved paths in which the chains travel and means for 25 transmitting motion to said curved members.

FRED WAITE.
